(57) **CLAIM**

The ornamental design for a desk as shown and described.

DESCRIPTION

FIG. 1 is a front, right perspective view of a desk showing our new design;

FIG. 2 is a front elevational view of the desk thereof;

FIG. 3 is a rear elevational view of the desk thereof;

FIG. 4 is a top plan view of the desk thereof;

FIG. 5 is a bottom plan view of the desk thereof;

FIG. 6 is a left elevational view of the desk thereof;

FIG. 7 is a right elevational view of the desk thereof;

FIG. 8 is a front, left perspective view of the desk thereof; and,

FIG. 9 is a front, right perspective view of the desk installed in a vehicle with the chair base in an alternate position. The broken lines in FIG. 9 depict environmental subject matter and form no part of the claimed design. All other broken lines in the drawings depict portions of the desk that form no part of the claim.

1 Claim, 9 Drawing Sheets
